ELECTRON MULTIPLIER

Rolf Möller, Berlin-Zehlendorf, and Fritz Below,
 Klein Machnow Post Berlin-Zehlendorf, Germany, assignors to the firm of Fernseh Aktien-Gesellschaft, Zehlendorf, near Berlin, Germany

Application December 4, 1936, Serial No. 114,286
 In Germany January 31, 1936

4 Claims. (Cl. 250—27)

The invention deals with a modulation circuit using photo-electric tubes and adapted, for example, for television purposes, and relates more particularly to a type of photo-electric tube containing a plurality of electrodes having high secondary emission qualities adapted for multiplying the photo electrons.

In modulating a carrier frequency with the aid of a photo-electric tube it is generally required that the amplitude of the carrier frequency be modulated with respect to a given constant basic value. In some cases it is desired that this basic value be kept as small as possible, say even equal to zero.

In order to attain this end the circuit of the invention is so arranged that a screening device adapted to screen off the carrier frequency is interposed between the electrode to which the carrier frequency is applied and the anode. The carrier frequency is, for example, applied to an electrode which is separated from the anode by one or more secondarily emitting electrodes constituted as screen electrodes. High frequency will therefore only be produced at the anode when the photo cathode is illuminated, as long as (even in non-illuminated condition) a small capacity disposed between the first electrode carrying the carrier frequency and the anode does not permit the high frequency to pass into the output circuit. This capacity however, in practice, is so greatly reduced by the screen arrangement that it no longer plays any part in most instances.

This arrangement however would also have the drawback that low frequency would be produced in the output circuit in addition to the modulated carrier frequency. In order to prevent this, two similar electrode systems are incorporated into the photo-electric tube in accordance with the invention and these obtain their electrons from the same photo cathode. The corresponding first electrodes of both systems are controlled in push-pull fashion from the carrier frequency generator through agency of a transformer. The result of this is that only one system is always in operation. The electrode of the other system during the corresponding half cycle is negatively biased to such an extent that no electron current can flow. The half wave trains of the modulated high frequency originating from both systems are united at the output into a complete wave train. The low frequency produced within the tube is equal in phase with both halves and is accentuated.

The drawing illustrates embodiments of the

subject matter of the invention. Referring to the drawing:

Fig. 1 represents a photo electric tube according to the invention.

Fig. 2 shows a photo electric tube containing two separate electrode systems.

Fig. 3 is a circuit containing a photo-electric tube according to Fig. 2.

The photo electric tube 1 of Fig. 1 contains a photo cathode 2 and an electrode system comprising grids 3, 4, 5, and anode 6. The grids 4 and 5 and the anode 6 receive a potential from a battery or a device connected to a power line which potential increases from grid to grid. The carrier frequency generator is connected to grid 3. The grids 4 and 5 are constituted as screen grids and have such a shape that the electrons do not find any free passage around grids 4 and 5. A special wall coating 7 may also be provided for this purpose, connected with diaphragm-like rings and carrying about 20 volts with respect to the cathode. This wall coating at the same time serves to prevent negative wall charges. The electrodes 4' and 5' are either connected with the grids 4 and 5 or led outside by means of separate terminals. In this case it is preferable to give the electrodes 4' and 5' a more positive potential than the last accelerating electrode. The number of accelerating and retarding electrodes may be varied depending on the degree of amplification desired. Furthermore, according to the invention the screen arrangement is applicable to tubes in which the electrodes are not formed of grid structures but rather as plates or partly as grids and partly as plates as illustrated in Fig. 2, or even as wires. The best type of screening can be determined after the electrodes have received their final shape commensurate with attaining as high a degree of amplification as possible.

The arrangement of Fig. 3 shows a photo electric tube 1 having two electrode systems. The two grids 3 are controlled in push-pull fashion by a carrier frequency generator 9 through a transformer 8. The grids 4 and 5 are likewise formed as screen grids as shown in Fig. 1. They are attached to tap-off points of battery 16 and may also for example, have the shape shown in Fig. 2 wherein a portion of the screen electrodes 4 and 5 are of solid plate construction. They are so shaped that the electrons cannot strike over from the cathode-facing high frequency carrying electrode to the anode 6. From anode 6 the currents are led through a transformer 10, a circuit 11 and to an amplifier 12. The modulated high fre-

quency composed of two half-wave trains is obtained from transformer 10 whereas the low frequency components are mutually suppressed. 4' and 5' have the same significance as in Fig. 1.

- 5 In order to be able to compensate for variations in both systems, condensers 13, which may also, if desired, be replaced by resistances, may for example be connected into the output. By moving the contact terminal 14 at transformer 10 10 the systems may be so compensated that the low frequencies are removed in an unobjectionable and complete manner. This displacement may for example also be effected by winding the primary coil in two halves so that these two 15 halves may be varied separately or in common in opposite direction as to their positional inductivity with respect to the secondary coil.

By means of a photo electric tube built in accordance with the invention the constant basic 20 value of the modulated high frequency becomes extraordinarily small. In order to give it a definite desired value or in order to equalize capacity variations, variable neutralizing condensers 15 are preferably used. These are either cross connected or may also be applied direct between the first grid and the anode of one and the same electrode system.

The photo electric tube may also embody two push-pull connected electrode systems without 30 the provision of screen electrodes. This is possible in all cases in which compensation of the carrier frequency is not involved but rather a compensation of the modulation frequency.

We claim:

- 35 1. In combination, an electron discharge device comprising an envelope having therein a source of electrons, an anode, a control electrode disposed between said cathode and said anode and arranged to receive high-frequency potentials, secondary electron emissive electrodes positioned substantially to enclose said anode to electrostatically shield said anode from said control electrode, at least two of said secondary electron emissive electrodes being disposed between the anode and control electrode, means for energizing said anode to a potential positive with respect to said source of electrons, and means for energizing said secondary electron emissive electrodes to positive potentials having values intermediate that existing between said source of electrons and said anode.
- 40 2. In combination, a source of potentials of relatively high frequency, an evacuated envelope having therein a source of electrons, an anode, a control electrode disposed between said source of electrons and said anode, means for impressing high-frequency potentials from said first-mentioned source on said control electrode, and means for electrostatically shielding said anode from said control electrode while increasing by secondary-electron emission the magnitude of the stream

of electrons which flows from said source of electrons to said anode, said last-mentioned means including secondary electron emissive electrodes positioned substantially to enclose said anode, at least two of said secondary electron emissive 5 electrodes being disposed between the anode and control electrode, means for energizing said anode to a potential positive with respect to said source of electrons, and means for energizing said emissive electrodes to positive potentials having 10 values intermediate that existing between said cathode and said anode.

3. In combination, an evacuated envelope having therein a source of electrons, an anode, a control electrode positioned between said source 15 of electrons, and said anode, means for energizing said anode to a potential positive with respect to said source of electrons, means for impressing potentials of relatively high frequency on said control electrode to control the stream of electrons flowing from 20 said source to said anode in accordance with said high-frequency potentials, and means for electrostatically shielding said anode from said control electrode while increasing by secondary 25 electron emission the magnitude of the stream which flows from said source to said anode, said last-mentioned means comprising secondary electron emissive electrodes positioned substantially to enclose said anode, at least two of said secondary 30 electron emissive electrodes being disposed between the anode and control electrode, said secondary electron emissive electrodes being energized to positive potentials having values intermediate that between said cathode and said anode, a conductive wall coating on said envelope 35 in cooperative relation to said shielding electrodes to complete an enclosure for said anode, and means for maintaining said coating at a substantially fixed potential relative to said source of electrons.

4. An electron discharge device comprising a source of electrons common to a plurality of output electrodes, a control electrode for each of said output electrodes, each of said output electrodes normally having an undesirable capacity with its 45 control electrode, and electron multiplying electrodes individual to each of said output electrodes for substantially enclosing each of said output electrodes in an electrostatic shield thereby to preclude flow of capacitive current from each of 50 said output electrodes to its control electrode, at least two of said electron multiplying electrodes being disposed between each output electrode and its associated control electrode, said multiplying electrodes simultaneously increasing by electron 55 emission the magnitude of the stream of electrons which flows from said source to said output electrodes.
